[57] CLAIM

The ornamental design for a Christmas decoration, substantially as shown and described.

DESCRIPTION

FIG. 1 is a side elevation of a Christmas decoration showing my new design; the undisclosed opposite side is a mirror image of the side shown;

FIG. 2 is a top plan view thereof;

FIG. 3 is a front elevation taken in the direction of line 3—3 of FIG. 2;

FIG. 4 is a rear elevation taken in the direction of line 4—4 of FIG. 2; and

FIG. 5 is a bottom plan view thereof.
